Patented Jan. 8, 1918.

UNITED STATES PATENT OFFICE.

MICHAEL J. BREEN, OF LOUISVILLE, KENTUCKY.

GAGE-GLASS.

1,252,656.

Specification of Letters Patent. Patented Jan. 8, 1918.

Application filed June 16, 1915, Serial No. 34,392. Renewed November 20, 1917. Serial No. 203,061.

To all whom it may concern:

Be it known that I, MICHAEL J. BREEN, a citizen of the United States, residing at Louisville, in the county of Jefferson and 5 State of Kentucky, have invented certain new and useful Improvements in Gage-Glasses, of which the following is a specification.

This invention relates to gage glasses employed in connection with steam boilers to 10 indicate the height of water in the boiler.

The invention has for its object to provide an improved glass tube constructed of wire glass, the embedded wire netting being so 15 arranged that the gage can be easily read.

A further object of the invention is to provide a novel and improved device for cleaning the tube without removal from the boiler.

20 The objects stated are attained by means of a combination and arrangement of parts to be hereinafter described and claimed, and in order that the invention may be better understood, reference is had to the accompanying drawing, in which—

Figure 1 is a side elevation of a gage glass constructed in accordance with the invention; Fig. 2 is a vertical section of the glass, and Fig. 3 is a horizontal section 30 thereof.

Referring specifically to the drawing, 5 denotes the glass tube of the gage, the same being connected at its ends to the boiler by suitable metal couplings 6 and 7, respectively. The top coupling has a stuffing box 8 which is in line with the tube and above the upper end thereof. Through this stuffing box a rod 9 passes down into the top coupling, said rod being in alinement with 35 the tube. The rod carries a swab 10 at its lower end designed to enter the tube for the purpose of removing sediment therefrom. The rod is slideable, and upon pushing it downward, the swab enters the tube and 40 wipes the same clean on the inside. The rod is long enough so that the swab may be pushed down to the lower end of the tube, and below this end of the tube the bottom coupling 7 has a pocket 11 to receive the 45 sediment brought down by the swab. The 50

socket has an outlet for the removal of the sediment, and said outlet is closed by a screw plug 12. The rod 9 is normally in raised position so as to locate the swab 10 in the top coupling 6, thereby leaving the 55 glass tube 5 entirely unobstructed.

The tube 5 is made of wire glass, the wire netting 13 embedded in the glass having longitudinal openings in front and at the sides of the tube extending throughout a substantial portion of the length of the tube, thus leaving the tube unobstructed at these places to give a clear view of the water column from different positions. These openings are made in the netting before the same is 60 embedded in the glass, and the netting is also painted or enameled red. This distinctive coloring of the netting forms a background for the water column and makes the gage very easy to read. As the netting 65 is embedded in the glass the color remains clear and unsoiled. A glass tube reinforced as herein described requires no metal casing, the wire netting giving sufficient strength to the glass to withstand the pressure. 70

The preferred embodiment of the invention has been shown but it will be evident that various changes and modifications may be made without departure from the spirit and scope of the invention as claimed hereinafter. 75

I claim:

The combination with a gage glass, and top and bottom couplings for connection with the boiler; of a slideable rod extending 80 into the top coupling in alinement with the glass and having a swab at its lower end, the bottom coupling having a sediment pocket located beneath the lower end of the glass and in communication therewith, and 85 having a clean-out opening, said pocket being an unobstructed chamber of greater 90 width than the diameter of the glass, and a closure for the clean-out opening. 95

In testimony whereof I affix my signature in presence of two witnesses.

MICHAEL J. BREEN.
